RAZOR

Justin E. Ross, Kansas City, Mo.

Application August 20, 1941, Serial No. 407,582

9 Claims. (Cl. 30—62)

This invention relates to improvements in razors and particularly to razors of the safety type in which a relatively thin blade is carried by a blade-supporting member.

When using the safety razors now being marketed it is appreciated that in replacing a used blade or removing a blade for cleaning it is difficult to manipulate the various parts, also there is the danger of cutting the fingers.

The principal object of the present invention is the provision of a magnetic blade-carrying member on which a blade is held between outwardly projecting bosses by magnetic force.

Another object of this invention is the provision of a razor comprising a blade-supporting member having undercut bosses and a permanent magnet, a blade made of magnetic material positioned on said blade supporting member with edges thereof in engagement with said undercut bosses and with the body of the blade in operative relation with said permanent magnet.

A further object of the invention is the provision of a razor having a novel handle which permits of proper positioning of the blade when shaving without interfering with the body of the operator.

Other objects are simplicity and economy of construction, ease, speed and efficiency of operation, and adaptability for use with the various types of razor blades now in general use.

Reference will now be had to the drawing wherein:

Figure 1 is a side elevation of a razor embodying this invention.

Fig. 2 is a front elevation of the razor.

Fig. 3 is an enlarged plan view of the blade-carrying member with the blade in operative position thereon.

Fig. 4 is an enlarged plan view of the blade-carrying member with the blade removed.

Fig. 5 is a fragmentary sectional view taken on line V—V of Fig. 3.

Fig. 6 is a sectional view taken on line VI—VI of Fig. 3.

Fig. 7 is a fragmentary sectional view taken on line VII—VII of Fig. 3.

Fig. 8 is a perspective view of one of the permanent magnets detached.

Fig. 9 is an enlarged plan view of a modified form of the blade-holding member and the blade.

Throughout the several views like reference characters refer to similar parts and the numeral 10 designates a blade-carrying member made of brass or any other suitable nonferrous material. Member 10 is substantially rectangular

in shape to conform to the shape of blade to be used. A handle 12 of unique shape and form is secured by rivets 14 to the blade-supporting member. It will be noted that the handle is disposed obliquely to the blade bearing surface 16 of the member 10 and has an outwardly curved outer end 18 which recedes from the body being shaved. This form of handle allows for the proper angled relation of the blade to the surface being shaved and also prevents objectional contact of the outer end of the handle with parts of the chest as the razor is moved to the various shaving positions.

Finger and thumb gripping depressions 20, 22 and 24 are slightly checked to insure a good holding means and are symmetrical at both sides of the center plane to fit either the right or left hand of the operator. The handle may be made from any suitable material but is especially suited for molding from some of the plastic materials.

The perforated cap 26 is fitted over the inner end of handle 12, and is secured thereto by rivet 28, with the ears 30, positioned against the back side of member 10 to receive rivets 14.

The blade-supporting member 10 is rounded at its lower edge to form a guard bar 32 adjacent the elongated slot 34 which extends substantially the full length of the member 10. The lower edge portion of member 10 is slightly offset to form a surface 36 slightly below the blade bearing surface 16.

When the blade 38 is in the operative position with its major body portion resting on surface 16 of member 10 it will overlap a portion of slot 34 with the cutting edge thereof positioned in spaced relation to surface 36 and slightly above the upper edge of guard bar 32 to present suitable shaving relation of the parts.

The guard bar 32 is provided with two series of diagonally positioned ridges 40 and 42 which are so related that the ridge of the two series diverge upwardly and serve to spread and smooth the skin just below the cutting edge of the blade to facilitate smooth and clean shaving. The outer end portions of member 10 are recessed to form notches 44 for reasons hereinafter set forth.

The blade 38, best shown in Figs. 3 and 5, is substantially rectangular in form and is notched at 46 at each of its four corners to form end tongues 48 which bridges across the notches 44 thereby presenting a good finger grip for placing and removing and adjusting the blade. An undercut boss 50 is formed at each of the upper corners of the member 10. The lower side of each boss 50 is undercut to form a notch 52 to receive the edge portion of blade 38 as clearly

shown in Figs. 3 and 7. It will be noted that when the blade is in the operative position as shown in Fig. 3 the notched corners will receive the bosses 50 to prevent any material longitudinal movement of the blade and will also preclude any vertical transverse movement thereof. Plain bosses 54 adjacent each of the opposite lower corners of the member 10 are so related to the lower corner notches 44 of the blade 38 as to permit the blade to be laid flat on the surface 16 for adjustment into notches 52.

When the blade is in the operative position as shown in Fig. 3 it will be noted that the upper corners of the blade are slightly below the upper ends of bosses 50 and the lower corners of the blade are slightly above the lower extremities of bosses 54, thereby guarding the cutting corners of the blade to prevent accidental injury to the operator. The upper edge of blade 38 is spaced inwardly from the outer edge of member 10. The blade shown is of the double cutting edge type which has a central opening 56 which extends lengthwise thereof and has an enlargement 58 adjacent the central portion of the blade. The central portion of the blade-supporting member is provided with an undercut boss 60 having an overhanging lip 62 which overhangs the blade about enlargement 58 to prevent the upward movement of the central portion of the blade when it is in the operative position. The depth of the undercut notch 64 in boss 60 is much greater than the depth of notches 52 so that when the blade is fully seated in notches 52 in bosses 50 the blade metal about opening 58 will not contact the bottom of notch 64 in boss 60.

One of the principal objects of the present invention is to secure the blade in position on the blade-supporting member by means of a magnet or a plurality of magnets, and for the purpose of controlling and properly applying the magnetic force it has been found expedient to make the handle and blade-supporting member of a non-ferrous material.

The magnet 66, best shown in perspective in Fig. 8, is rectangular in shape cut away on one of its faces to produce four pole pieces 68 which are adapted to be snugly fitted into openings 70 formed through the body of member 10 so that the surface of the poles will be in the plane of the blade bearing surface 16. The magnet is preferably of the permanent type and can be made of any suitable material. Many alloys have been developed that have extremely high magnetic qualities and when these alloys are used smaller magnets will have sufficient force of pull to hold the blade in position.

The magnets may be molded, formed or otherwise produced and are secured in position by means of rivets 72 fitted into hole 74 and extending through a hole formed through the member 10.

In the present showing two similar magnets are shown, one on each side of the handle.

The double-edge blade is so constructed that it can be turned over or the edges reversed. Single-edged blades or substantially any type of blade made of a magnetic material can be used in conjunction with this type of blade holder since the principal requirement is that the blade be held in position on the blade-supporting member by magnetic force.

In the modified form shown in Fig. 9 two semi-circular openings 76 are shown on the transverse medial line of the blade 80 to receive the undercut boss 78. This special type of blade has less

of the metal cut away thus presenting more metal to be attracted by the magnet. The guard bar 82 in this form is shown plain.

Many changes in the shape and relative relation of the parts can be made without departing from the spirit of the invention and it is the desire to be limited only by the scope of the appended claims.

I claim:

10. A razor comprising a blade-supporting member having spaced apart bosses at its opposite ends, to receive a blade therebetween for limited transverse and longitudinal movement, and a permanent magnet carried by said blade-supporting member whereby said blade is secured in the operative position between said bosses.
15. A razor comprising a blade-supporting member having a depending handle and upwardly projecting, spaced apart, undercut bosses, a flat blade of ferrous material adapted to rest on said blade-supporting member, and a magnet carried by said blade-supporting member to contact and secure said blade in the operative position with its rear edge disposed beneath said undercut bosses.
20. A razor comprising a blade-supporting member having a handle fixed thereto, undercut bosses formed on the upper face of said blade-supporting member, a ferrous blade adapted to be positioned on said blade-supporting member with edges thereof disposed beneath said undercut bosses, and a magnet carried by said blade-supporting member to urge said blade toward said blade-supporting member.
25. A razor comprising a blade-supporting member having a handle fixed thereto, undercut bosses formed on the upper face of said blade-supporting member, a ferrous blade adapted to be positioned on said blade-supporting member with edges thereof disposed beneath said undercut bosses, and a magnet carried by said blade-supporting member to urge said blade toward said blade-supporting member.
30. A razor comprising a blade-supporting member having a depending handle, an undercut boss formed at each of the outer, upper extremities of said blade-supporting member, an undercut boss adjacent the central portion of said blade-supporting member, a perforated blade adapted to rest on said blade-supporting member with its upper edges in engagement with said upper undercut bosses and with the edge of the blade adjacent said perforation disposed beneath said centrally disposed undercut boss, and a permanent magnet carried by said blade supporting member to urge said blade toward said blade-supporting member.
35. A razor comprising a blade-supporting member having a depending handle, an undercut boss formed adjacent each of the outer, upper corners of the blade-supporting member, an undercut boss formed adjacent the central portion of the blade-carrying member, a flat ferrous blade having an opening formed adjacent its central portion adapted to rest on said blade-supporting member with its upper edge engaging said undercut upper bosses as the central undercut boss extends through said blade opening to overlap the blade adjacent said opening, and a permanent magnet carried by said blade-supporting member to urge said blade against said blade-supporting member.
40. A razor comprising a blade-supporting member having a depending handle, an undercut boss formed adjacent each of the outer, upper corners of the blade-supporting member, an undercut boss formed adjacent the central portion of the blade-carrying member, a flat ferrous blade having an opening formed adjacent its central portion adapted to rest on said blade-supporting member with its upper edge engaging said undercut upper bosses as the central undercut boss extends through said blade opening to overlap the blade adjacent said opening, and a permanent magnet carried by said blade-supporting member to urge said blade against said blade-supporting member.
45. A razor comprising a blade-supporting member having a depending handle, an undercut boss formed adjacent each of the outer, upper corners of the blade-supporting member, an undercut boss formed adjacent the central portion of the blade-carrying member, a flat ferrous blade having an opening formed adjacent its central portion adapted to rest on said blade-supporting member with its upper edge engaging said undercut upper bosses as the central undercut boss extends through said blade opening to overlap the blade adjacent said opening, and a permanent magnet carried by said blade-supporting member to urge said blade against said blade-supporting member.
50. A razor comprising a blade-supporting member having a depending handle, an undercut boss formed adjacent each of the outer, upper corners of the blade-supporting member, an undercut boss formed adjacent the central portion of the blade-carrying member, a flat ferrous blade having an opening formed adjacent its central portion adapted to rest on said blade-supporting member with its upper edge engaging said undercut upper bosses as the central undercut boss extends through said blade opening to overlap the blade adjacent said opening, and a permanent magnet carried by said blade-supporting member to urge said blade against said blade-supporting member.
55. A razor comprising a blade-supporting member having a depending handle, an undercut boss formed adjacent each of the outer, upper corners of the blade-supporting member, an undercut boss formed adjacent the central portion of the blade-carrying member, a flat ferrous blade having an opening formed adjacent its central portion adapted to rest on said blade-supporting member with its upper edge engaging said undercut upper bosses as the central undercut boss extends through said blade opening to overlap the blade adjacent said opening, and a permanent magnet carried by said blade-supporting member to urge said blade against said blade-supporting member.
60. A razor comprising a blade-supporting member having a guard bar provided with two series of upwardly diverging ridges, spaced apart bosses formed on the outer surface of said blade-supporting member, a permanent magnet carried by said blade-supporting member, and a ferrous blade positioned on said blade-supporting member between said bosses to contact said permanent magnet.
65. A razor comprising a blade-supporting member having a guard bar provided with two series of upwardly diverging ridges, spaced apart bosses formed on the outer surface of said blade-supporting member, a permanent magnet carried by said blade-supporting member, and a ferrous blade positioned on said blade-supporting member between said bosses to contact said permanent magnet.
70. A razor comprising a blade-supporting member having bights formed in its opposite ends, a

permanent magnet carried by said blade-supporting member between said bights, a blade mounted on said blade-supporting member in contact with said magnet and with its end portions respectively overlapping said bights, and a downwardly and outwardly curved handle secured to said blade-supporting member.

8. In a razor of the class described, a blade-supporting member, a permanent magnet carried by said blade-supporting member, bosses formed on the outer face of said blade-supporting member, a blade having transversely spaced apart openings adjacent its central portion adapted to be positioned on said blade-supporting member with one of said bosses extending through one of said openings and certain of the other of said bosses engaging the upper edge of said blade.

9. A razor comprising an outwardly curved handle, a rectangular blade-supporting member secured obliquely to said handle, bights formed in the opposite ends of said blade-supporting member, bosses integral with said blade supporting member and extending outwardly from the outer

face thereof, two series of downwardly diverging ridges formed along one edge of said blade supporting member, an undercut boss formed on the outer surface of said blade-supporting member adjacent the center thereof, a pair of spaced apart undercut bosses extending outwardly from the upper end portions of said blade-supporting member, a substantially rectangular blade notched at each of its four corners and provided at its center portion with a transversely disposed opening, said blade being adapted to be positioned on said blade-supporting member to overlap said bights and with said pair of undercut bosses engaging the notches formed in the upper portions of said blade and with the center undercut notch overlapping the blade adjacent said center opening, and a permanent magnet carried by said blade-supporting member at each end portion thereof to respectively contact the opposite end portions of said blade to secure it in the operative position with certain of the edge portions of said blade positioned below said first named notches.

JUSTIN E. ROSS.
